UNITED STATES PATENT OFFICE

2,651,786

COMBINATION CRIB AND PLAYPEN

John Jay Field, Pocatello, Idaho

Application May 27, 1948, Serial No. 29,602

7 Claims. (Cl. 5—93)

1

This invention relates to new and useful improvements in furniture for children, and the primary object of the present invention is to provide a novel and improved combination crib and play pen for children.

Another important object of the present invention is to provide a combination crib and play pen including a slidable side member or panel and embodying novel and improved means for simultaneously locking the slidable side member in a raised position as the same is manually raised or lifted.

A further object of the present invention is to provide a crib structure having a mattress supporting platform, a pivotal support carried by the crib and disposed beneath the platform for holding the mattress when the platform is employed as a play table or board, and including a gravity actuated latch for retaining the pivotal support in a normally raised position.

A still further aim of the present invention is to provide a combination crib and play pen of the aforementioned character that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention, and showing the mattress removed therefrom;

Figure 2 is a transverse vertical sectional view of the present invention, showing the mattress applied to the pivotal support, and with dotted lines showing the pivotal support in a lowered position and the mattress disposed on the platform;

Figure 3 is a transverse vertical sectional view taken substantially on the plane of section line 3—3 of Figure 1;

Figure 4 is an enlarged transverse horizontal sectional view taken substantially on the plane of section line 4—4 of Fig. 2; and

Figure 5 is a perspective view of one the 50 gravity-actuated latches used in conjunction with the present invention.

Referring now to the drawings in detail, wherein, for the purpose of illustration, there is disclosed a preferred embodiment of the present

2

invention, the numerals 10 and 12 represent a headboard and footboard, respectively, to the vertical side edges of which there are fixed support posts or legs 14 and 16.

5 Suitably fixed between the end members or the headboard and footboard 10 and 12 is a substantially horizontal platform or fixed support 18 having a pair of spaced parallel, longitudinal side rails 20 and 22.

10 A fixed side member or side rail 24 is suitably fixed between the legs 14 of the end members 10 and 12, and this side member 24 includes a lower horizontal bar or rail 26 and a plurality of spaced parallel vertical rails 28.

15 The remaining legs of the end members 10 and 12, namely, the legs 16, are provided with opposed, substantially vertical, dovetail grooves 30 that terminate adjacent the upper ends of the legs 16.

20 The numeral 32 represents a movable or slidable side member or panel having dovetailed side edges or ends 34 that slidably engage the grooves 30. The side member 32 includes a lower horizontal rail 36 and a plurality of spaced parallel vertical bars or rails 38.

25 Pivotedly secured to the side rail 20 of the fixed support or platform 18, as at 40, is a hook member 42 having a flat bearing portion 44 and inclined bearing portions 46. The portions 46 are adapted to engage the inclined edges 48 of the lower rail 36 of the side member 32 and the portion 44 is adapted to rest against the flat lower edge 50 of rail 36 to retain the said side member 32 in a normally raised and locked position, as shown by full lines in Figure 3.

30 Integrally formed with the upper end of the hook member 42 is an arm 52 that supports a weight 54 that will normally urge the portions 44 and 46 of the hook member 42 under the rail 36.

35 When the side member 32 is raised, the upper inclined edge 56 of the side rail 36 will engage the outermost of the bearing portions 46 of the hook member 42 to pivot the hook member 42 to its dotted line position, as shown in Figure 3 of the drawings, whereby the weight 54 will urge the hook outwardly to engage under the side rail 36.

40 Pivoted as at 58 to the legs 16, below the platform 18, are the ends of a longitudinal side bar 60 of a pivotal lower support 62 that is normally retained in a substantially horizontal position beneath the platform 18 by a holding latch which is designated generally by the numeral 64.

45 The latch 64 is pivoted to a hook element 65

that depends from the central portion of the side rail 26. This latch 64 includes a hook member 66 having an inclined free end portion 68 that will engage the remaining longitudinal side bar 60 of the lower support 62 as the same is raised to pivot the hook member 66 outwardly, whereupon a weight 70 attached to the hook member will pivot the hook member 66 inwardly so that the same will engage under the side bar 60a.

When the mattress 72 for the present crib is not disposed on the platform 18, the same is placed on the lower support 62 as shown best in Figure 2 of the drawings.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. In a combination crib and play pen, a pair of end members, a rigid imperforate elongated platform terminally fixed to said end members, a pair of side members carried by said end members, a mattress support pivoted to said end members beneath said platform and coextensive therewith for downward swinging movement, and means carried by one of the side members for retaining the support in a raised and locked position and spaced sufficiently from said platform to permit a mattress to be positioned between the platform and the support to be supported on the latter.

2. In a combination crib and play pen, a pair of end members, an imperforate and rigid bottom wall permanently secured to said end members, a pair of side members carried by said end members, a mattress support pivoted to said end members and mounted beneath said bottom wall and coextensive therewith and a latch carried by one of said side members lockably engaging said support to hold the latter against pivotal movement and spaced sufficiently from the bottom wall to permit a mattress to be placed on the support and beneath the bottom wall.

3. In a combination crib and play pen, a pair of end members, a rigid and imperforate wall secured in horizontally disposed position to said end members, a pair of side members carried by said end members, a mattress support pivoted to said end members and mounted beneath said wall and in coextensive relation therewith, and a pivotal, gravity-actuated latch carried by one of said side members lockably engaging said support to retain the latter in a raised position and spaced sufficiently from the

wall to permit a mattress to be held on the support and beneath the wall.

4. A combination crib and play pen comprising a box-like member having an elevated, flat, rigid imperforate bottom wall, a support pivoted to the member beneath the bottom wall for vertical swinging movement toward and away from the bottom wall and underlying the bottom wall and being disposed coextensive therewith, said support being located sufficiently below the bottom wall to permit a mattress to be held on the support below the wall, and latch means carried by the member engaging and supporting the support horizontally beneath the wall.

5. In a play pen including a pair of end walls, a pair of side walls joining the end walls and a flat, imperforate, rigid bottom wall permanently secured to the end walls, an open frame member coextensive with the bottom wall and pivoted to said end walls beneath said bottom wall for vertical swinging movement toward and away from the bottom wall, and a single latch mounted on one of said side walls medially between said end walls and engaging and holding the frame member against pivotal movement.

6. In a combination crib and play pen, a pair of end members, a rigid imperforate elongated platform terminally fixed to said end members, a pair of side members carried by said end members, a mattress support pivoted to said end members beneath said platform and coextensive therewith for downward swinging movement, a pivotal wire hook carried by one of said side members for engaging and retaining the support in a raised and locked position, said hook having a portion engageable with the support as the latter is raised so that the hook will be swung clear of the support, and means carried by the hook for urging the hook to a position for engaging said support.

7. The combination of claim 6 wherein said last mentioned means includes a weight.

JOHN JAY FIELD.
